United States Patent Office.

GEORGE T. PALMER, OF BROOKLYN, NEW YORK.

Letters Patent No. 77,207, dated April 28, 1868; antedated April 14, 1868.

IMPROVED MOSQUITO-NET FRAME.

The Schedule referred to in these Letters Patent and making part of the same.

TO ALL WHOM IT MAY CONCERN:

Be it known that I, GEORGE T. PALMER, of Brooklyn, in the county of Kings, in the State of New York, have invented a new and improved Mode of Making a Mosquito-Net and Canopy-Frame for a bed, or to be attached to a bedstead; and I do hereby declare that the following is a full and exact description thereof, reference being had to the accompanying drawings, and to the letters of reference marked thereon.

The nature of my invention consists in making a mosquito-net canopy, the frame of which is pivoted over the centre of the bed, and is provided with radially-folding arms, so that it may be folded back, and the ends of the arms be over the head of the bedstead, and the curtains being folded with it, be entirely freed from the bed, and leaving free access thereto.

Another feature of my improved canopy-frame is, providing it with rods for the purpose of folding or opening the canopy-frame, whereby the frame can be set or folded with ease by a person standing on the floor of a room; also of an easy method of attaching and supporting the canopy to the bedstead, the parts of which I will proceed to explain by referring to the drawings, in which—

Figure 1 is a plan view of a canopy-frame provided with radial arms pivoted to a central support.

Figure 2 is a view of the canopy-frame supported by a bracket and rod, and showing the radial arms folded back over the head of the bed.

Figure 3 is a top view of the frame showing the arms folded.

Figure 4 is a side view of the folded frame with the central support removed.

Figure 5 shows the mosquito-net and canopy-frame attached to a bedstead.

Figure 6 shows a modification of fig. 1, adapted for use on a child's crib.

Figures 7 and 8 show a support for the canopy-rod.

Like letters indicate corresponding parts in all the figures.

In figs. 1, 2, *d* is a disk, on which are pivoted the radial arms *a a a a*. *C* is a support to the disk *d*. *c* is a standard, to which the cords *e* are attached. *B* is a bracket-support to the part *C*. *g* is a rod attached to the bracket *B*. The radial arms open and close at the point *a'*.

In fig. 5, *ff* are pendent rods, which are attached, one to each of the radial arms which fold together.

In figs. 7 and 8, *A* shows a portion of the underneath edge of the head of the bedstead, and to which is secured the strap *h*. *D* is a socket to receive and support the rod *g*. *i* is a lip or tongue to the socket *D*, which fits into a suitable space between the strap *h* and the lower edge of the head of the bedstead. The socket-support or strap *h* is firmly screwed to the under edge of the head of the bedstead, and the socket may be attached or withdrawn, at pleasure, when it is required to set up the canopy or to remove it.

The radial arms are pivoted upon the central support *d*, and supported at their swinging ends by the cords or braces *e*. The ends of the arms are provided with a point-pin or hook, which is shown by *a'' a''*, fig. 4. The pins *a''* may be fixed to or fitted in sockets in the ends of the arms. The mosquito-net is provided with suitable eyeleted holes, and at the proper distances to fit upon the hooks, as a support when the arms are extended. The radial arms which come together when the canopy is spread are provided at one of their ends with a hook or other suitable device to catch and secure the ends, and retain them locked together, when required, and capable of being uncatched or unlocked by means of the rods *ff*.

To operate the canopy-frame, take hold of the rods *ff*, and after unhooking the arms, swing the radial arms to the required position, when the arms and curtains may be folded back over the head of the bed, as shown by fig. 2. To fold the frame, bring the two rods together, and lock the arms at the upper end of the rods, when the canopy-net will enfold the bed.

A canopy-net and frame made after my improved manner will be convenient, easily managed, and capable of being folded completely away from the bed.

Having thus described my improved mosquito-net canopy-frame, I claim—

1. A radially-folding mosquito-net canopy-frame composed of folding-arms *eee*, disk or support *d*, and supporting-arm *C*, made substantially as and for the purpose shown and described.

2. Supporting a radially-folding canopy-frame from under its centre by means of the standard B and supporting-arm C, when the arm C extends over the bed and the folding frame is pivoted thereon, substantially as shown.
3. The rods *ff* suspended from the folding-arms of a mosquito-net frame, for the purpose of folding and unfolding the frame, substantially as shown.
4. The pins *a'' a''*, in combination with a radially-folding mosquito-net frame, whether said pins are affixed to the arms of the frame or fitted in sockets at the ends of the arms, for the purpose described.
5. Supporting the radially-folding arms of a mosquito-net canopy-frame by supporting-braces pivoted to the upright, *c*, substantially as shown.

GEORGE T. PALMER.
